WRIST WATCH SPRING BAR

Nunzio Guarnieri, New Orleans, La.

Application December 5, 1946, Serial No. 714,203

1 Claim. (Cl. 24—265)

1 The present invention relates to improvements in wrist watch spring bar and relates more particularly to the spring dowel bars commonly used to attach wrist watches to wrist bands or bracelets.

An object of the invention is to provide an improved spring bar construction in which the length of the bar is regulatable to fit differential distances between the wrist watch lug holes, the arrangement providing for detachable sections on either or both the tube and the plunger whereby one or both may be shortened by the removability of such detachable sections or may be correspondingly lengthened by the addition of sections or clippings removed from other spring bars where the same are not needed.

Another object of the invention is to secure the spring in the receiving pipe or tube whereby the same may not fall out, this resulting in the greater simplicity of construction and more facile assembly.

A still further object of the invention resides in so constructing the closed end of the receiving pipe or tube that the same has a double function of pinching the terminal end of the spring and thus anchoring the spring in the tube, and in the second place forming a fixed trunnion or plug pin which enters one of the lug holes of the wrist watch.

With the foregoing and other objects in view, the invention will be more fully described hereinafter and more particularly pointed out in the appended claims.

In the drawings, in which like parts are denoted by the same reference characters throughout the several views,

Figure 1 is a side elevation of an improved wrist watch spring bar constructed in accordance with the present invention.

Figure 2 is a longitudinal section taken on the line 2—2 in Figure 1.

Figure 3 is an end elevation looking from the left end of Figure 2.

Figure 4 is a transverse section taken on the line 4—4 in Figure 1.

Figure 5 is a similar section taken on the line 5—5 in Figure 1.

Figure 6 is a side elevational view of a form of plunger or length bar employed.

Referring more particularly to the drawings, 10 designates a receiving pipe or tube having an open end 11 and a closed end 12. Circular grooves 14 are made in the external wall of the tube 10. One such groove is spaced from the open end 11 by a predetermined distance and

the other grooves may be spaced like distances apart. The grooves form ridges between the same. The walls of the grooves are preferably convergent inwardly to a point or annular line 5 and such grooves may penetrate any desired distance into the material of which the tube 10 is made. The grooves 14 so placed and formed produce planes of definitive weakness wherever occurring and the sections or clippings of the 10 tube 10 may be readily broken off along these planes so that the resultant clippings form rings.

The closed end 12 of the tube 10 may be tapered and reduced as by spirining or other desired operation into a reduced diameter to provide a stationary plug pin or trunnion 15 which is also tubular in form and produces interiorly a narrow neck in which the long terminal end 16 of the helical spring 17 is pinched in the act 20 of drawing the metal 15 together. This long terminal end 16 is preferably brought off from the helix 17 in alignment with the axis of such helix and thus has the effect to hold the spring 17 in a central position within the tube 10 and to prevent such spring from dropping out of the tube 10.

Slidably mounted through the open end 11 of the tube 10 is the length bar or plunger 18 which may be made from a solid round bar of metal. 30 This plunger 18 has formed or carries at one end thereof a plug pin or trunnion 19. V-shaped or other circular grooves 20 are formed at axially spaced intervals on the plunger 18 beginning from the inner end thereof for the same purpose 35 as the grooves 14, namely that such plunger 18 may be shortened by breaking off sections thereof along the planes defined by the grooves 20 which will cause the shearing to be accomplished along straight lines and the break to be clean.

40 In the use of the device, the receiving pipe or tube 10 initially receives the spring 17 and has the reduced trunnion end 15 pinched together upon such terminal end 16. The plunger 18 may be then freely introduced into the open end 11 of the tube 10 and made to engage the free end of the coil spring 17. The arrangement will be such 45 that the tube 10 and the plunger 18 must be moved together to compress the spring 17 in order that the trunnions 15 and 19 shall fit between the lugs of the wrist watch frame, whereupon the spring 17 will move the trunnions apart and into the lug holes.

As an example merely but to which it will be understood that I am not limited in dimensions, 55 a spring bar will be put on the market in the

most popular length size of $\frac{5}{8}$ of an inch. If a longer spring bar is needed than the normal $\frac{5}{8}$ " bar, one has only to remove the plunger 18 and insert into the receiving pipe or tube 10 one of the clippings from a previous operation. After this is done, the plunger 18 may be replaced in the tube 10. If the gap between the wrist watch lug holes is shorter than $\frac{5}{8}$ of an inch, the jeweler may begin tearing or cutting one or more of the sections or clippings from the plunger 18, and also if desired from the receiving pipe or tube 10, until the required over-all length is reached. The improved spring bar can easily be built up to reach a length of an inch and a quarter and may be shortened down to a quarter of an inch. By anchoring the coil spring 17 in the receiving tube 10, the attention of the jeweler is taken away from any need of holding the spring in place or uprighting the open end 11 of the tube 10 while assembling the plunger 18 thereto. This simplifies the manual assembly.

It will be noted that this new type of manufacture makes the band stronger particularly where the integral trunnion 15 is fashioned from the closed end of the receiving tube 10.

It will also be noted that the improved construction is simple and safe, inexpensive and easy to remove for changes of different watch attachments such as bands, straps, etc. The invention provides a rigid construction which will not bend easily and which will hold firmly to any watch. The devices may be made of stainless steel or any other non-corrosive metals, as well as brass, to insure long life and durability.

The length bar 18 as shown in Figure 6 may be made as a solid bar or as a hollow bar, the same as the receiving pipe 10. If the length bar is made in the hollow form, the spring 17 may be placed therein besides being attached to the stationary plug pin 15. Thus, more spring action 40 may be obtained if desired.

The pipe 10 may be made as long as desired. The greater the length the greater the stability of the spring bar as a whole.

While I have disclosed herein the best form of the invention known to me at the present time, I desire it to be understood that I reserve the right to make changes and modifications in the herein described embodiment of the invention provided such changes fall within the scope of the following claim.

What I claim is:

A wrist watch spring bar comprising a receiving tube having one end open, a plug pin on the opposite end of the tube, a plunger slidably received by said tube through its open end, a plug pin on the outer end of the plunger, and resilient means for spreading the plunger and tube, the tube and plunger having a series of spaced apart circular grooves providing detachable sections longitudinally of the tube and plunger, the walls of each groove converging inwardly to an annular line lying in a single plane providing planes of definitive weakness along which a selected section may be sheared along a straight line to produce a clean break.

NUNZIO GUARNIERI.
